ATTORNEY

UNITED STATES PATENT OFFICE.

JOHN L. FLEMING, OF PEORIA, ILLINOIS.

PLUMBING APPARATUS.

Application filed July 23, 1921. Serial No. 487,137.

To all whom it may concern:

Be it known that I, JOHN L. FLEMING, a citizen of the United States, residing at Peoria, in the county of Peoria and State 5 of Illinois, have invented new and useful Improvements in Plumbing Apparatus, of which the following is a specification.

This invention relates to plumbing apparatus, particularly to toilets, and has for its 10 object the provision of a toilet flushing device which is so constructed that it includes a bowl which always contains a relatively large amount of water which when caused to flow or withdraw from the bowl will cause a 15 sufficient suction to remove the entire contents of the bowl, the arrangement being such that the flush will be absolutely silent.

An important and more specific object is the provision of a toilet flush of this character 20 which is so constructed that the bowl is always substantially full of water so that any matter deposited therein in the ordinary course of events will be withdrawn by a suction upon the opening of a manually controllable valve, the device further including a plurality of valves which will operate, subsequently to the flushing and cleansing of the bowl, to insure the refilling of the bowl and the refilling of an auxiliary tank 25 whereby the bowl will always be in condition ready for use.

Another object is the provision of a device of this character in which the inlet valve is so constructed as to eliminate the 30 usual noise incident to the filling of tanks of this character.

Still another object is the provision of a device of this character which is provided with means which will automatically operate 40 to prevent any possible flooding of the bowl and consequent wetting of the floor of the bath-room or other rooms in which the device is located in any case of stoppage of the outlet pipe on account of an accumulation of paper or the like.

An additional object is the provision of a device of this character which is very readily cleaned in as much as the outlet pipe is straight and leads directly into the waste 45 pipe of the building.

An additional object is the provision of a device of this character which will be simple and inexpensive in manufacture and installation, highly efficient in use, positive

in action, durable in service and a general 55 improvement in the art.

With the above and other objects and advantages in view, the invention consists in the details of construction to be hereinafter more fully described and claimed, and illustrated in the accompanying drawings in which,

Figure 1 is a longitudinal sectional view through the preferred form of my invention,

Figure 2 is a longitudinal sectional view 65 through a modified form.

Referring more particularly to the drawings and especially to Figure 1, I have shown my device as comprising a tank 10 and a toilet bowl 11. It should be understood in advance that this tank and bowl may be formed in such shape as to be disposed in either spaced relation to a wall, against a wall, or else to be so constructed as to be located within a corner of a toilet 75 room or bath-room. The tank 10 may be opened at its top or may be closed if preferred, and the bowl 11 is naturally preferably provided at its top with any suitable closure of the ordinary type. The numeral 80 12 designates the outlet or waste pipe of a building and the numeral 13 designates the outlet pipe of the bowl 11, this pipe leading into the bowl and joining onto the waste pipe 12 by any suitable connection preferred. 85

Leading into the back wall of the upper portion of the tank 10 is an inlet pipe 14 connected with the water supply pipe of the building and connected within the tank with a suitable valve casing 15 having a valve 90 seat 16. This valve casing 15 may be of any desired shape though in actual practice I have found it advisable to make it of spherical or ball like form and of comparatively heavy weight whereby the weight 95 thereof will operate to reduce the noise incident to the passage of water through it. Connected with the upper end of this valve casing 15 is a pipe 17 which leads into ring like outlet pipe 18 located around the top 100 of the bowl 11 and provided with a plurality of perforations 19 designed to discharge the water passing therethrough downwardly.

Connected with the pipe 13 is an upwardly extending pipe 20 which has its upper end 105 formed with a reflex bend or goose-neck 21 which is designed to act as a siphon, the free end of this goose-neck 21 extending below

the intended water level in the bowl and tank so that in the event of excessive filling of the tank and bowl, the water therein will be drawn out through the pipe 20 and be 5 discharged into the pipe 13.

Associated with the valve 16 in the inlet valve casing 15 is a vertically movable valve member 22 carried by a stem 23 which is pivotally connected with a pivoted lever 24 10 which is provided at its other end with a float 25 disposed within the tank adjacent the rear wall of the bowl 11.

Located at the end of the pipe 13 where it enters the bowl 11 is a vertically swingable flat valve 26 pivoted as shown at 27 adapted to close the entrance end of the pipe 13, and pivotally connected with the free end of this flat valve 26 is a vertically movable rod or wire member 28 which has 20 its upper end extending through the top of the casing and provided with an operating handle or knob 29. It is of course to be understood that suitable guide members are provided for holding this rod 28 in proper 25 position. It should also be stated that the lower portion of the forward wall of the tank 10 is provided with an opening 30 which leads into the space behind the lower edge of the rear wall of the bowl 11 as 30 clearly shown so that there will be communication between the tank 10 and the bowl 11.

The numeral 31 designates a pipe or conduit which is located within the lower portion 35 of the bowl 11 and which leads into the tank 10 at a point above the pipe 13 and which communicates with the interior of the bowl through an opening 31^a. At its end leading into the tank 10, this pipe 31 is provided with a swingable valve 32 which is pivoted intermediate its ends and which has connected therewith a float arm 33 carrying a float 34.

Pivoted upon the upper portion of the 45 front wall 35 of the tank portion of the device, as shown at 36, is a lever arm 37 with which is pivotally connected a downwardly extending rod 38 which has its lower end carrying a float 39. The other end of this 50 lever 37 has connected therewith a downwardly extending arm 40 which carries a catch member 41 adapted to be engaged by a catch or projection 42 upon a vertically movable rod 28.

55 The operation of the device is as follows: Assuming that the tank 10 and the bowl 11 are full to the level indicated by the dotted line, after the toilet has been used, it is merely necessary that the user pull upwardly upon the handle or knob 29 whereupon the valve 26 will be unseated. As soon as the valve 26 is unseated, the water within the bowl 11 will naturally pass out through the pipe 13 into the waste pipe 12 and this 60 action will of course naturally result in a

considerable degree of suction which will insure absolute emptying of the bowl 11 not only of the clear water therein but of any contents which may have been deposited thereinto. As the water in the bowl 11 flows 70

out, the float 25 will naturally drop down which will result in opening the valve 22 whereupon water from the supply pipe will pass through the inlet pipe 14, valve casing 15, valve seat 16, and pipe 17 into the pipe 75 18 at the top of the bowl from which the water will flow downwardly through the perforations 19 into the bowl 11. When the bowl is flushed as above described, it is to be understood that the tank 10 still remains 80

full of water. When the water within the bowl and front portion of the tank lowers to a sufficient extent, the float 34 will drop down whereupon the valve 32 associated therewith by means of the arm 33 will open 85 whereupon the water within the lower portion of the tank 10 will flow into the lower end of the bowl through the pipe 31. By the time the water in the tank drops below the float 39, the bowl 11 is cleaned whereupon the float 39 will drop down. It should be stated that when the device is first flushed by pulling upwardly on the handle or knob 29, the catch member 42 will engage the catch 41 whereby to hold the flat valve 26 90 in open position. When the water level within the tank 10 has dropped below the float 39, it is apparent that the float 39 will drop whereupon the lever 37 will be rocked upon its pivot 36 to cause the latch member 100

41 to disengage the catch 42 whereupon the flat valve 26 will drop down to its original position closing the entrance end of the pipe 13. All this action occurs before the water level within the tank 10 gets to a sufficiently low degree to cause any rushing noise within the device. It is of course to be understood that the flat valve 26 should be made comparatively heavy so that it will automatically gravitationally return to closed position the moment that the latch member 41 is disengaged from the catch 42 105 carried by the rod 28.

As the bowl 11 is refilled, water therein enters the tank through the opening 30, 110 which incidentally is provided with a suitable check valve 38^a. If the inlet valve mechanism should ever leak, it is of course readily apparent that the discharge or overflow pipe 20 having the goose-neck 21 will 115 effectively take care of any surplus supply of water so as to prevent possible flooding of the bowl 11 and consequent wetting of the floor. Another feature in the provision of the goose-neck is that this goose-neck will 120 prevent any possible escape of sewer gas into the device. Owing to the fact that the valve 26 is normally closed and covered by water, it will be apparent that no trap is 125 necessary in the construction of this toilet. 130

When the bowl 11 and tank 10 have been refilled, it is of course apparent that when the water level reaches that indicated by the dotted line in Figure 1, the float 25 will operate to move the valve 22 downwardly so as to cut-off the flow of water so that the device will be in its initial position. This operation is of course gone through with every time the bowl is used and emptied by 10 pulling upon the handle 29.

In the form shown in Figure 2, the numeral 70 designates the tank with which is associated the bowl 71 which is similar to both of the above described forms. The numeral 72 designates the outlet pipe which leads from the bottom of the device through the waste pipe of the building as clearly shown. Normally closing the inlet end of the pipe 72 is a hollow ball 73, formed of 20 rubber with which is associated a vertically movable rod 74 provided above the top of the tank and bowl with an operating knob or handle 75. Pivoted within the lower portion of the tank as shown at 76 is a lever 77 which has one end provided with a depending float 78 and which has its other end provided with a float 79 which is seated upon the upper end of an elbow 80 which leads into the front portion of the tank, it being 25 noted that the front portion of the tank communicates with the lower end of the bowl as clearly shown. The same type of inlet valve controlled mechanism is shown in this form of the device as in the first two described forms and it is believed that a further explanation of such is unnecessary.

In the operation of this form of the device it will be apparent that when the operator pulls upon the knob or handle 75 and 40 lifts the valve 73 from its seat, the water within the bowl will rush out whereupon sufficient suction will be caused to thoroughly cleanse the bowl. The float 73 being hollow, will remain off of its seat until the water 45 level within the device falls below the level of the float 78, whereupon the float 78 will drop and this will result in elevation of the float 79 whereupon the water within the tank or back portion of the device will enter the 50 front portion or bowl of the device. As the bowl empties it is of course apparent that

the suction of the water rushing out through the pipe 72 will cause the float 73 to be drawn down and reseated tightly.

From the foregoing description and a 55 study of the drawings it will be apparent that I have thus provided a simply constructed and highly efficient plumbing fixture or toilet which will be highly efficient in every way, which will not likely get out of 60 order, which will be inexpensive in upkeep and which will be very silent in operation.

While I have shown and described the preferred embodiment of my invention, it is of course to be understood that I reserve the 65 right to make such changes in the form, construction and arrangement of parts as will not depart from the spirit of the invention or the scope of the subjoined claim.

Having thus described my invention I 70 claim,

A device of the character described comprising a tank portion and a bowl portion communicating therewith at the lower end, a check valve within said point of communication, an outlet pipe leading from the lower end of the bowl portion and adapted for connection with the waste pipe of a building, a valve normally closing the inlet end of said outlet pipe, a vertically movable rod 75 member connected with said valve and provided above the top of the tank and bowl with an operating handle, an inlet pipe, a valve casing upon said pipe, at the upper portion of the tank portion, a valve within 80 said valve casing adapted to close and cut-off the inlet of water thereinto, a lever arm pivotally mounted and connected with said last named valve, a float on said lever arm, a latch means for holding said rod in elevated 90 position when it has been moved to unseat said first named valve, a depending rod connected with said latch mechanism and carrying a float whereby when the water level drops to a certain degree said latch member 95 will be released to permit said first named valve to close, and float controlled means for controlling flow of water from said tank into said bowl.

In testimony whereof I affix my signature. 100

JOHN L. FLEMING.
